UNITED STATES PATENT OFFICE.

EDWIN T. MARSH, OF ROCHESTER, NEW YORK.

CONVERTIBLE CHAIR.

No. 926,992.

Specification of Letters Patent.

Patented July 6, 1909.

Application filed November 23, 1908. Serial No. 464,010.

To all whom it may concern:

Be it known that I, EDWIN T. MARSH, a citizen of the United States, residing at Rochester, in the county of Monroe and 5 State of New York, have invented certain new and useful Improvements in Convertible Chairs; and I do declare the following to be a full, clear, and exact description of the invention, such as will enable others skilled in 10 the art to which it appertains to make and use the same.

This invention relates to improvements in convertible chairs.

The object of the invention is to provide a 15 chair having means whereby the same may be quickly converted into a bed or couch.

A further object is to provide a chair of 20 this character in which is arranged a compartment for holding the bedding to be used when the chair is converted into a bed or couch, and having means for holding the bedding in position when the chair is arranged in the form of a bed or couch.

With these and other objects in view, the 25 invention consists of certain novel features of construction, combination and arrangement of parts as will be described and particularly pointed out in the appended claim.

In the accompanying drawings, Figure 1 30 is a perspective view of a chair constructed in accordance with the invention, showing the parts arranged for use as a chair or seat; Fig. 2 is a central longitudinal sectional view of the same; Fig. 3 is a cross sectional view 35 on the line 3—3 of Fig. 2; Fig. 4 is a plan view of the chair arranged in the form of a bed or couch; Fig. 5 is a central longitudinal sectional view of the same; Fig. 6 is a vertical cross sectional view on the line 6—6 of 40 Fig. 4.

Referring more particularly to the drawings, 1 denotes the chair which has the general structure or form of a Morris chair, and consists of a seat portion, 2, having sides, 3, 45 arms, 4, and supporting legs, 5. The seat portion is fixedly connected to the inner sides of the upper portion of the legs, 5, and has a seat provided with suitable springs, and may be upholstered in any preferred manner.

50 Below the seat portion and connected to the inner sides of the legs, 5, adjacent to their lower ends is a supporting frame, 6, on which rests a foot section or extension, 7, said foot section comprising a frame having suitable 55 springs and is preferably upholstered to correspond with the seat portion 2. Hinged to

the outer end of the foot section are supporting legs, 8, said legs being adapted to be folded upwardly into engagement with the under side of the foot section preferably to 60 lie between the side bars of the frame. On the opposite end of the frame adjacent to each corner are secured apertured connecting plates, 9, which are adapted to be engaged with suitable pins or hooks, 10, arranged on 65 the front cross bar of the seat portion, whereby the inner end of the foot section is supported and held in operative engagement with the seat. When the foot section is thus engaged with the seat, the outer end of said 70 section is supported by means of the legs, 8, which are opened out to an operative position. Slidably mounted in the opposite sides of the foot section, 7, are holding plates, 12, which are provided on their outer edge 75 with upwardly projecting flanges, 13, and are held in sliding engagement with the sides of the foot section by means of pins, 14, which engage slots, 15, formed in the plates as shown. The plates 12 when drawn out 80 serve as lateral extensions for the foot section, while the flanges 13 on said plate serve to prevent the bedding from slipping laterally off the sides of the foot section.

Loosely arranged below the seat 2 and the 85 foot section 7 when the latter is in an inoperative position on the frame 6 is a tray or receptacle 16 adapted to receive the bedding employed in connection with the chair when the latter is arranged as a bed or 90 couch. The tray 16 may be readily withdrawn from and replaced in the frame, beneath the foot section and provides a convenient storing place for the bedding when the latter is not in use. The front and back 95 of the seat portion of the chair are suitably inclosed so that when the foot extension and the tray are in a folded or inoperative position, they will be hidden from view.

Hingedly connected in any suitable manner to the upper portion of the rear supporting legs or other convenient part of the seat portion of the chair is a back section 17, said section comprising a frame 18 on which is arranged a suitable spring and which is provided with upholstering to correspond with the upholstering of the seat and foot sections of the chair. The back section is supported in an operative position as a chair back by means of the usual or any suitable 105 supporting mechanism, the same being here shown as a pawl 19 pivotally connected at 110

its upper end to one side of the back frame and adapted to be engaged at its lower end with the teeth of a rack 20, secured to the rear side of one of the supporting legs of the 5 chair.

When the chair is arranged in the form of a bed the back section, 17, is let down substantially on a level with the seat portion and said back section is supported at its 10 outer end by legs, 21, which are hingedly connected to the rear side of the back section and are adapted to fold inwardly on the back section in an out-of-the-way position when the back section is arranged for 15 use as a chair back. Arranged on the outer or upper side of the back section, adjacent to the opposite edges thereof, are holding strips, 22, which are preferably of an ornamental structure, and designed to prevent 20 the bedding from slipping laterally off this portion of the chair when the same is arranged in the form of a bed or couch.

A chair constructed as herein shown and described may be quickly converted from a 25 chair to a bed, or vice versa, and when arranged as a chair will form a comfortable seat, with all indications of a bed structure entirely hidden.

From the foregoing description, taken in 30 connection with the accompanying drawing, the construction and operation of the invention will be readily understood without requiring a more extended explanation.

Various changes in the form, proportion

and the minor details of construction may 35 be resorted to without departing from the principle or sacrificing any of the advantages of the invention as defined in the appended claim.

Having thus described my invention, what 40 I claim as new and desire to secure by Letters-Patent, is:

In a convertible chair, a seat section, a foldable foot section adapted to be engaged with said seat section to support the inner 45 end of the foot section in operative position, foldable legs connected to said foot section to support the latter in an operative position, extension plates slidably mounted in the opposite sides of said foot section, flanges arranged on said extension plates to hold the bedding in place on said section, a back section hingedly connected to the seat section and adapted to be folded down to form a portion of the bed or couch, foldable supporting legs 50 connected to said back section to support the latter in an operative position, and holding strips arranged on the opposite edges of the back section to prevent the bedding from slipping laterally therefrom.

In testimony whereof I have hereunto set my hand in presence of two subscribing witnesses.

EDWIN T. MARSH.
